SPOON

William F. Kayhoe, 1007 Baldwin Road,
Richmond, Va. 23229

Filed Mar. 30, 1973, Ser. No. 346,255

Term of patent 14 years

Int. Cl. D7—03

U.S. Cl. D7—137

FIG. 1 is a front elevational view of a spoon showing my new design;

FIG. 2 is a side elevational view thereof;

FIG. 3 is a back elevational view thereof; and

FIG. 4 is an enlarged section on the line 4—4 of FIG. 1.

I claim:

The ornamental design for a spoon, substantially as shown and described.
